ATTORNEY

UNITED STATES PATENT OFFICE.

EDWARD T. ADAMS, OF LOS ANGELES, AND JOHN B. REILLY, OF WHITTIER, CALIFORNIA, ASSIGNORS TO JOSEPH G. RICHARDSON, OF LOS ANGELES, CALIFORNIA.

DOUBLE-ACTING HOLLOW-PLUNGER PUMP.

Application filed August 27, 1924. Serial No. 734,408.

To all whom it may concern:

Be it known that we, EDWARD T. ADAMS and JOHN B. REILLY, citizens of the United States, and residents of Los Angeles, California, and Whittier, California, respectively, have invented new and useful Improvements in Double-Acting Hollow-Plunger Pumps, of which the following is a specification.

10 The present invention relates to deep well pumps of that general type in which there is provided a so called standing tube, while the plunger is made up of two other tubes; one working inside of the standing tube and the other working outside of the standing tube. The result is that an annular space exists between the two plunger tubes; said space increasing in volume with the outward stroke of the plunger and decreasing with the inward stroke of the plunger. The above described arrangement of tubes provides a labyrinthine path through which fluid must travel before it can pass the plunger, and as a consequence it is generally believed that the leakage or slip is thereby reduced. However, the incompressible fluid leaking into the annular space during outward movement of the plunger must be displaced therefrom during the inward stroke 25 of the plunger in order to allow the plunger to descend. The energy required to force the fluid out again is practically wasted, and in addition, some of the oil is forced to pass the plunger and leakage is thereby actually encouraged.

Another outstanding advantage of such pumps is that sand will find its way into the annular space and will remain there, eventually preventing proper descent of the plunger and finally stalling the pump. In the pump shown by Miller in his Patent No. 1,483,369, a plurality of ports are provided in the innermost plunger tube so that the annular space is vented. The objection to Miller's pump is, that in perforating the inner plunger tube, one of the objects of the tube is defeated. In other words, fluid reaching the annular space by leakage may pass directly through the ports without appreciable resistance, whereas, if the ports were not there, such fluid before reaching the interior of the inner plunger tube, would have to pass through the small working clearance between the inner plunger tube 55 and the standing tube,

It is the prime object of the invention to provide improvements in pumps of the above mentioned type whereby the annular space may be properly vented for ejection of leakage and sand, without defeating the purpose of the inner plunger tube. 60

Another object of the invention is to provide a pump in which the resistance to leakage is increased over previous pumps of the above mentioned type, particularly inasmuch as it is advisable to allow large working clearances without greatly reducing the efficiency of the pump. 65

Another object of the invention is to provide means whereby the increasing volume of the annular space does not cause an abnormal pressure reduction to the extent that leakage is actually encouraged. Still other objects and advantages will appear hereinafter. 70

We have illustrated by the accompanying drawings a preferred embodiment of our invention.

In the said drawings:

Figure 1 is a view in vertical section of the said embodiment; 80

Figure 2 is a view in section seen on a line 2-2 of Figure 1;

Figure 3 is a view in section thereof seen on a line 3-3 of Figure 1. 85

In carrying out this form of invention we provide an annular casing wall 5 which incloses the pump chamber B. The wall is provided at the lower end with a closure wall 6, having a central upwardly ranging suction aperture A. Aperture A terminates at an annular valve seat 9 on which rests a ball 10. The valve seat and ball are hereinafter referred to as the standing valve. It will be understood that the pump casing continues upward to connect with discharge tubing, (not shown) which leads to the surface to provide a continuous fluid course into and through which fluid handled by the pump, is carried to the surface. 90

The bore A' of the well is lined with casting 11. The pressure of oil contained in A and A' will always be that equal to the normal level of the fluid contained in the well while the pressure in B will always be that imposed by the column of fluid reaching from the standing valve to the top of the well. Since the normal oil level in wells which require pumping, is always well below the surface it is obvious that the pressure in 105 110

B will always be considerably in excess of the pressure in A and A'.

The pump is provided with a reciprocal plunger head 12 from which depends an annular wall 14. Said wall is hereinafter referred to as the outer plunger wall, and its outer diameter is appreciably less than the inner diameter of the pump casing, so that solid matter, such as sand, may settle into space B'.

To the plunger head there is attached a common ball cage 15, having an externally threaded boss 16 whereby the plunger may be connected to the usual sucker rods (not shown).

In conformance with a salient feature of this invention the pump chamber is provided internally with an inner coaxial wall 17 which is hereinafter referred to as the standing tube. The outer plunger tube is a working fit over the outside of the standing tube. The interior space encompassed by the standing tube is indicated by the letter C and is in one-way communication with A through the standing valve. An inner plunger wall 18 is provided which depends from the plunger and which is a working fit within the standing tube. In conformance with a salient feature of the invention, a valve seat 19 is provided within the inner plunger wall, and upon said seat there repose a ball 21 which is limited in its upward movement by a transverse pin 22. It will be apparent now that as the plunger walls are reciprocated relative to the pump casing, that the inner plunger wall will co-act with the standing tube in the same way in which a plunger ordinarily co-acts with a stationary pump barrel. In other words, during the up stroke of the plunger space C will increase in volume and become filled with oil and during the down stroke the working valve carried by the inner plunger wall will be moved downward through the oil; the standing valve preventing oil which has reached C from returning to A. An annular space E exists between the inner and outer plunger walls, into which space the standing tube extends.

It will be observed that while space C is increasing in volume space E will also be increasing in volume, during the up stroke. During the down stroke these spaces will decrease in volume. The inner plunger wall is provided with a plurality of ports leading into space E, as in the case of the pumps mentioned heretofore. For the purpose of preventing fluid flowing from points above the pump back through the ports 23 to space E, we provide a ball 25 resting on the seat provided by the upper valve cage.

The operation of the pump will be understood from the following: During the up stroke of the plunger space C increases in volume and oil is induced therein through

the standing valve. At the same time the oil existing in B and above ball 25 will be raised and therefore during the up stroke of the plunger a very considerable amount of oil will be displaced; the effective area of the plunger on the up stroke being that of the internal area of the pump casing. It will also be seen that during the up stroke of the pump space E will be increasing in volume. Now the instant that the space E begins to increase in volume the pressure of fluid or gas existing therein will be reduced. Fluid cannot flow from B into the space E because of the ball 25; the ball therefore serving to prevent slippage from B back into E. The space E will therefore draw fluid from the space D, which is internally of the inner plunger wall. This space D can be supplied with oil only through the lower working valve and standing valve. Therefore during the up stroke of the pump the plunger is not only acting to draw oil through the standing valve into the space C, but it is also acting to cause oil to flow into the space E from C, through the working valve. The fact that the standing valve and lower working valve are both open during the up stroke of the plunger is an advantageous peculiarity of this pump.

In other words, space E is really an auxiliary pump chamber. During the down stroke of the plunger, which would be ineffective for displacing oil were it not for the space E, said space is decreased in volume and a part of the oil contained therein is forced outwardly. This oil is double checked from flowing downwardly because of the two valves below the port. Therefore, the oil displaced will be forced through the ports and will raise ball 25 and be forced upward through the pump casing and tubing. It will be apparent now that we have provided a pump having two pumping chambers, in which pump the up stroke of the plunger is the suction stroke for both pump chambers, whereas the down stroke of the plunger is a discharge stroke for one of the chambers while the up stroke is the discharge for the other chamber. Or, in other words, we have provided a double pump in which a double suction stroke and a single discharge stroke is accomplished by the upward movement of the plunger while the second single discharge stroke is accomplished by the down stroke of the plunger.

Any sand or silt which may settle from the oil contained in B would tend to lodge upon the cylinder head and eventually find its way into space B'. Of course a certain amount of leakage will exist between the co-acting annular walls of the casing and plunger respectively, and we will now consider the operation of the pump in so far as leakage, and self-cleaning features are

concerned. In the following discussion two conditions will be assumed, namely, that in which a slippage between the casing wall and the outer plunger wall is slight, and that in which such leakage is excessive to the point that it will flow into space E as rapidly as space E is increased. It will be understood that during the down stroke of the plunger all the chambers within the pump are subject to the maximum pressure and there can be no leakage from B to E or from B to C by way of E; providing of course the valves are tight. In the instance where the leakage is slight space E will be subject to a suction pressure which will be substantially that of the pressure then existing in space C and as a consequence there will be no tendency for oil to leak from E to C by way of the space between the inner plunger wall and the standing tube. Of course during the upward stroke space E is of reduced pressure and therefore there may be leakage from B into E. This leakage will carry the sand from the plunger head into the lower portion of space E. As oil is drawn into E from D during the up stroke of the pump the oil contained in E will be considerably agitated and will pick up sand which has found its way to the lower part of space E. The sand in suspension with the oil will be ejected, during the down stroke of the pump, from the space E, through the ports and into the column of oil which is then rising relatively through the fluid course D. The conclusion to be drawn from the foregoing, is that with normal leakage no sand or oil will find its way from B to C by way of the space E and therefore any tendency of the space C to become clogged with precipitated sand is practically precluded.

Assuming a condition in which leakage is excessive from B to E: during the up stroke of the plunger space E will increase in volume but will not draw any oil from D or C or A because of the fact that the volume of E is filled with leakage as rapidly as that volume is created. It is therefore apparent that during the up stroke of the plunger the oil contained in E will be at a pressure about midway between that of the oil contained in A and that of the oil contained in B. Therefore there will be a tendency for oil to leak from the annular space E into the space C above the standing valve. Now under these very unfavorable conditions the worst condition that can arise is leakage of oil from E to C and such leakage merely represents a loss in duty for the pump; such loss is not a commercial consideration in pumping deep wells because of the fact that the prime condition to be avoided is that of carrying sand past the plunger into internal chambers of the pump such as C. By preventing sand from pass-

ing through the clearance between the inner plunger tube and the standing tube the life of the wearing surfaces will be greatly increased. It is to be noted particularly that the leakage which is spoken of from E to C occurs during the up stroke of the plunger and except under very favorable conditions there will always be a slight induction of oil into space E through the ports. Therefore the tendency of any sand in suspension, is to remain in suspension in the lower parts of space E until a down stroke is effective in displacing it through the ports.

In considering the advantages of this construction and the resistance to leakage of the relatively reciprocating walls, it should be noted that there is considerable resistance offered to oil passing from space B to E. This resistance is that due to the small clearance between the standing tube and the outer plunger wall for a distance equal to the length of the plunger. That amount of resistance is all of the resistance that is ordinarily offered usual pumps. In this case, however, oil having found its way to E has only completed one-half of its journey to the space C and therefore, before any oil can leak from B to C it must pass through an exceptionally long and round-about course which offers great frictional resistance, and in which course there is provided the intermediate enlarged volume E which tends to collect the sand. While the ports are open at all times from E to D the upper valve 25 serves as a check to prevent oil from flowing from B through the ports into E, while the lower valve prevents oil taking a short cut from B to C by way of the ports.

We claim:

1. In a pump, a pump casing the interior of which is subject to the discharge pressure of the fluid pumped, an outer annular wall to said casing, an inner annular wall to said casing providing an intermediate annular space, a plunger member including an inner wall and an outer wall spaced apart and jointly reciprocal to provide a space into which the inner wall of the casing extends while acting to increase and decrease the effective volume of the annular space as the plunger is reciprocated relative to the casing walls, the inner wall of the plunger providing a central fluid course, a pair of spaced discharge valves in said course, and a port leading from the annular space to said central bore at a point between the said two discharge valves.

2. In a pump, a pump casing the interior of which is subject to the discharge pressure of the fluid pumped, an outer annular wall to said casing, an inner annular wall to said casing providing an intermediate annular space, a plunger member including an inner wall and an outer wall spaced apart

and jointly reciprocal to provide a space into which the inner wall of the casing extends while acting to increase and decrease the effective volume of the annular space as the plunger is reciprocated relative to the casing walls, the inner wall of the plunger providing a central fluid course, a pair of spaced discharge valves in said course, and a port leading from the annular space to 10 said central bore at a point between the said two discharge valves, and establishing constant communication therebetween.

3. In a pump, a pump casing the interior of which is subject to the discharge pressure of the fluid pumped, an outer annular wall to said casing, an inner annular wall to said casing providing an intermediate annular space, a plunger member including an inner wall and an outer wall spaced apart 20 and jointly reciprocal to provide a space into which the inner wall of the casing extends while acting to increase and decrease the effective volume of the annular space as the plunger is reciprocated relative to 25 the casing walls, the inner wall of the plunger providing a central fluid course, a pair of spaced discharge valves in said course, and a port leading from the annular space to said central bore at a point between the said two discharge valves, the casing walls and plunger walls so arranged that oil may escape from points immediately 30 external of the inner casing wall to points within the inner casing wall only by way 35 of the working clearances existing between the corresponding adjacent relatively reciprocal walls of the casing and plunger respectively.

4. In a pump, a pump casing the interior of which is subject to the discharge pressure of the fluid pumped, an outer annular wall to said casing, an inner annular wall to said casing providing an intermediate annular space, a plunger member including an 45 inner wall and an outer wall spaced apart and jointly reciprocal to provide a space into which the inner wall of the casing extends while acting to increase and decrease the effective volume of the annular space as the plunger is reciprocated relative to 50 the casing walls, the inner wall of the plunger providing a central fluid course, a pair of spaced discharge valves in said course, and a port leading from the annular space to said central bore at a point between the said two discharge valves, and establishing constant communication therebetween, the casing walls and plunger walls 55 so arranged that oil may escape from points immediately external of the inner casing wall to points within the inner casing wall only by way of the working clearances existing between the corresponding adjacent relatively reciprocal walls of the casing and 60 plunger, respectively.

5. In a pump, two relatively reciprocal members, each member having two spaced concentric annular walls, each of the walls of one member being disposed in close proximity to a corresponding one of the walls of the other member whereby an isolated annular space is provided which increases and decreases with relative reciprocation of the members, the innermost of the walls providing a central fluid course, 70 and spaced discharge valves within said fluid course, one of the walls being provided with a constantly open port leading from the said otherwise isolated space into the fluid course at a point intermediate of 75 the two valves.

6. In a pump, two relatively reciprocal members, each member having two spaced concentric annular walls, each of the walls of one member being disposed in close proximity to a corresponding one of the walls of the other member whereby an isolated annular space is provided which increases and decreases with relative reciprocation of the members, the innermost of the walls providing a central fluid course, 80 a suction non-return valve carried by one of the said members and opening upwardly into said fluid course, a discharge valve carried by one wall of the other member, an upper discharge valve carried by said member, and a port provided in the wall of said member leading from the annular space into the central fluid course between the two discharge valves.

7. In a pump, two relatively reciprocal members, each member having two spaced concentric annular walls, each of the walls of one member being disposed in close proximity to a corresponding one of the walls of the other member whereby an isolated annular space is provided which increases and decreases with relative reciprocation of the members, the innermost of the walls providing a central fluid course, 90 a suction valve and a discharge valve arranged to coact with the relatively reciprocating members to provide pumping action, a port leading from said central fluid course to said annular space, and means acting to prevent fluid flowing from said annular space to said suction valve by way of said central fluid course while permitting fluid to surge constantly back and forth through said port.

8. In a pump, a plunger embodying two coaxially arranged tubular members; one of smaller diameter than the other, a casing embodying two coaxially arranged tubular members; one of smaller diameter than the other, the plunger members coacting with the casing members to provide a main pump chamber and an auxiliary pump chamber separated from the main pump chamber by one of aforesaid tubular members, a standing valve, a pair of spaced working valves car- 100

ried by said plunger; and a port leading from said auxiliary pumping chamber to said main pumping chamber, through that member which separates said chambers, intermediate of the said working valves.

9. A pump plunger for pumps of the character described, embodying an outer tubular member and an inner tubular member; said plunger providing a central fluid course, a pair of spaced upwardly opening nonreturn valves for controlling flow of fluid in said fluid course, and a port penetrating the inner tubular member at a point intermediate of the said two valves.
10. In a pump, a pump casing having an inlet opening at its lower end provided with a standing valve, a standing tube extending

upwardly from said standing valve and spaced from said casing, a plunger provided with inner and outer walls sliding respectively on the inside and outside of the standing tube so as to form a main pump chamber within said inner plunger wall and an auxiliary pump chamber between said inner and outer plunger walls; said inner plunger wall being provided with a port establishing permanent communication between said main and auxiliary pump chambers, a working valve carried by said inner plunger wall above said port, and a working valve carried by said plunger wall below said port.

EDWARD T. ADAMS.
JOHN B. REILLY.
